UNITED STATES PATENT OFFICE.

JOSEPH HENRY MACK, OF PASSAIC, NEW JERSEY, ASSIGNOR TO M. LOWENSTEIN & SONS, INC., OF NEW YORK, N. Y., A CORPORATION OF NEW YORK.

DESIGN FOR A PRINTED FABRIC.

Application filed January 12, 1927. Serial No. 20,338. Term of patent 3½ years.

To all whom it may concern:

Be it known that I, JOSEPH H. MACK, a citizen of the United States of America, and a resident of Passaic, in the county of Passaic and State of New Jersey, have invented a new, original, and ornamental Design for Printed Fabric, of which the following is a specification.

Reference is to be had to the accompanying drawing in which the figure is a view of a swatch of fabric showing my new design.

I claim—

The ornamental design for a printed fabric as shown.

JOSEPH HENRY MACK.
